UNITED STATES PATENT OFFICE

GISBERT L. BOSSARD, OF DAYTON, OHIO, ASSIGNOR TO GENERAL KONTROLAR COMPANY, INC., OF DAYTON, OHIO, A CORPORATION OF OHIO

DESIGN FOR A CHIME COVER OR SIMILAR ARTICLE

Application filed May 1, 1931. Serial No. 39,684. Term of patent 14 years.

To all whom it may concern:

Be it known that I, GISBERT L. BOSSARD, a citizen of the United States of America, residing at Dayton, in the county of Montgomery, State of Ohio, have invented a new, original, and ornamental Design for Chime Cover or Similar Article, of which the following is a specification, reference being had to the accompanying drawings, forming a part thereof.

The design is illustrated in the accompanying drawings, in which—

Fig. 1 is a perspective view of the chime cover showing my new design; and

Fig. 2 is a front elevation of the chime cover on a reduced scale.

I claim:

The ornamental design for a chime cover or similar article, substantially as shown.

GISBERT L. BOSSARD.
